UNITED STATES PATENT OFFICE.

EDSON POTTER, OF ROCHESTER, NEW YORK.

COMBINED COLLAR-BUTTON AND NECKTIE SLIDE.

1,380,084.

Specification of Letters Patent. Patented Sept. 24, 1918.

Application filed January 4, 1918. Serial No. 219,400.

To all whom it may concern:

Be it known that I, EDSON POTTER, a citizen of the United States, residing at Rochester, in the county of Monroe and State of New York, have invented a new and useful Combined Collar-Button and Necktie-Slide, of which the following is a specification.

This invention has reference to combined collar buttons and necktie slides, and its object is to provide a device composed of a single piece of wire, so bent as to secure the collar to the neck band of a shirt, and provide a holding device for a necktie lodged within the collar.

The invention comprises a single piece of wire bent intermediately into a tongue from which side pieces extend to a greater length than the tongue, and are formed into coils with return parts constituting finger holds and entering members for insertion between the neck band of the shirt and the button hole tab thereof, while the coils serve to extend through and lock in the rear button hole of the collar, with the tongue inside the collar to constitute a neck tie slide.

The invention will be best understood from a consideration of the following detailed description, taken in connection with the accompanying drawing forming part of this specification, with the further understanding that, while the drawing shows a practical form of the invention, the latter is not confined to any strict conformity with the showing of the drawings but may be changed and modified so long as such changes and modifications come within the scope of the appended claims.

In the drawing:

Fig. 1 is an elevation of the rear face of the buttonhole portion of a collar showing the invention in place;

Fig. 2 is a section on the line 2—2 of Fig. 1, but including the neck band of a shirt;

Fig. 3 is an elevation of the collar button and necktie slide shown in Figs. 1 and 2;

Fig. 4 is an edge view thereof;

Fig. 5 is a section on the line 5—5 of Fig. 3;

Fig. 6 is a perspective view of the structure shown in the preceding figures;

Fig. 7 is a perspective view of a somewhat modified form thereof;

Fig. 8 is a perspective view of another modified form thereof.

Referring to the drawings, and more par-

ticularly to the structure of the invention shown in Figs. 1 to 6, there is illustrated a wire device 1, made of one piece bent intermediately into a tongue 2, from the base 60 of which proceed side pieces or legs 3 in normally divergent relation, one to the other, the tongue being bent to one side of the plane of the legs 3. At the end of each leg 3 remote from its junction with the tongue, the wire is formed into a coil 4 somewhat expanded axially. The coil 4 comprises a single turn from which there is an extension 5 of the wire in general line with the leg 3, but displaced therefrom by the amount of expansion of the coil 4. The extension 5 terminates in an open loop 6 from which there is a further continuation 7 terminating in a substantially closed loop 8 in line with the coil 4, the extension 7 diverging from the plane of the extension 5.

The arrangement is such that the tongue 2 is at one side of the plane of the legs 3, while the coils 4 and extensions 5 and 7 are located on the other side of the plane of the legs 3 from the tongue 2, and progressively recede from such plane.

The structure is elastic in the plane of the legs 3 due to the loop forming the tongue 2, and is quite rigid at the ends formed by the extensions 5 and 7, so that the latter may be grasped between the thumb and finger and caused to approach from a normally divergent relation into close relation. In the last-named condition, the tongue 2 and approaching legs 3 are readily introduced through the buttonhole opening 9 of a collar 10, so that the tongue 2 and legs 3 are located within the collar, with one-half of each coil 4 also within the collar. The elasticity of the device causes the loops 4 to expand to the limits of the collar buttonhole 9, leaving the other half of each loop 4 and the extensions 5 and 7 outside of the buttonhole band of the collar. The extensions 7 are separated from the collar because of the separation of the looped ends of these extensions from the coils 4. These extensions 7 are readily introduced behind the ordinary buttonhole flap or tab 11 of the neck band 12 of a shirt 13, the extensions 7 rising into the space between the tab 11 and neckband 12.

The collar button device is firmly though temporarily held in the collar, and is anchored to the neck band of the shirt in a manner to prevent it rising therefrom, there being no liability of the collar lowering to

a sufficient extent to escape from the shirt neck band. The collar itself is firmly anchored to the device by the engagement of the coils 4 through the buttonhole 9, the spreading tendency of the device serving to maintain the coils 4 at the ends of the buttonhole 9. The legs 3 rise up in the collar toward the top thereof between the two parts of the collar, and the tongue 2 being arranged at an angle to the plane of the two legs 3 forms a receptacle or slide for a necktie 14, the elasticity of the tongue causing it to yield to the pressure of the collar to bind the necktie against accidental shifting.

The forms shown in Figs. 7 and 8 are in the main the same as that shown in the preceding figures, and differ therefrom only in the configuration of the parts 5, 6, 7 and 8 of the structure shown in Figs. 1 to 6. In Fig. 7, the extension 5 is replaced by an extension 5^a, and the extension 7 is replaced by the extension 7^a, which latter terminates in a closed loop 8^a similar to the loop 8 of the preceding figures. The two extensions 5^a and 7^a cross each other instead of being side by side as in the preceding figures. The effect, however, is the same in each case.

In Fig. 8, the parts 5, 6 and 7 remain as before, but instead of a loop 8 there is another loop 8^b having one side prolonged as shown at 8^c toward the bend 6.

What is claimed is:

1. A combined collar button and necktie slide comprising a single piece of wire bent intermediately into a tongue, with the portions of the wire on opposite sides of the tongue forming divergent legs in a plane at an angle to the tongue, each leg terminating in a single axially expanded coil with an ex-

tension prolonged away from the coil lengthwise of the leg and away from the latter and terminating in another extension returned on the first extension with the end of the second extension spaced away from the coil at the end thereof remote from the corresponding leg.

2. A combined collar button and necktie slide comprising a single piece of wire bent intermediately into a tongue, with divergent legs on opposite sides of the tongue and elastically yieldable to forces to cause the legs to approach, each leg being formed into a coil at the end remote from the tongue, with the coil expanded away from the leg from the side thereof remote from the tongue, and having a prolongation away from the leg and returned upon itself toward the coil.

3. A combined collar button and necktie slide comprising a single piece of wire bent intermediately upon itself into a tongue with divergent legs on opposite sides thereof, said legs being elastically yieldable toward each other and each terminating in an axially expanded coil arranged to lock in the button-hole of a collar, with the legs and tongue within the collar, and each coil having a return continuation at the end of the coil remote from the legs and extended in a direction away from the tongue to engage behind the buttonhole flap or tab of a shirt neck band.

In testimony, that I claim the foregoing as my own, I have hereunto affixed my signature in the presence of two witnesses:

EDSON POTTER.
